DISPENSER FOR TAPE

Bjorn A. Larsen, Oslo, Norway, assignor to Sterling Coated Materials Ltd., Stalybridge, England, a British corporation

Filed June 21, 1963, Ser. No. 77,018

Claims priority, application Great Britain Jan. 16, 1963

Term of patent 7 years

(Cl. D74—1)

FIG. 1 is a side elevational view of a dispenser for tape showing my new design;

FIG. 2 is a front elevational view;

FIG. 3 is a rear elevational view;

FIG. 4 is a bottom plan view thereof; and

FIG. 5 is a perspective view of the side opposite to that shown in FIG. 1.

I claim:

The ornamental design for a dispenser for tape, substantially as shown.
